US00D691281S

(12) **United States Design Patent**
Walter et al.

(10) **Patent No.:** US D691,281 S
(45) **Date of Patent:** ** Oct. 8, 2013

(54) **MIXING ELEMENT**

(75) Inventors: **Alexander Walter**, Pürgen (DE); **Özcan Dönmez**, Landsberg am Lech (DE); **Korbinian Schepke-Gerlach**, Gauting (DE); **Emir Jelovac**, München (DE); **Manfred Harre**, Landsberg am Lech (DE); **Jens Gramann**, Gräfelfing (DE)

(73) Assignee: **3M Innovative Properties Company**, Saint Paul, MN (US)

(**) Term: **14 Years**

(21) Appl. No.: **29/398,419**

(22) Filed: **Jul. 29, 2011**

(30) **Foreign Application Priority Data**

Feb. 1, 2011 (EM) 001257497

(51) **LOC (9) Cl.** **23-01**

(52) **U.S. Cl.**

USPC **D24/220**

(57) **CLAIM**

The ornamental design for a mixing element, as shown and described.

DESCRIPTION

FIG. 1 is a perspective view of a design for a new mixing element;

FIG. 2 is a top view thereof;

FIG. 3 is a bottom view thereof;

FIG. 4 is a front view thereof;

FIG. 5 is a back view thereof;

FIG. 6 is a left side view thereof; and,

FIG. 7 is a right side view thereof.

The broken lines depict portions of the mixing element that form no part of the claimed design.

1 Claim, 3 Drawing Sheets
